UNITED STATES PATENT OFFICE.

MORTMORE QUIRY, OF MORGANFIELD, KENTUCKY.

DISK-SHARPENER.

1,004,817.

Specification of Letters Patent.

Patented Oct. 3, 1911.

Application filed April 27, 1911. Serial No. 623,799.

To all whom it may concern:

Be it known that I, MORTMORE QUIRY, a citizen of the United States, residing at Morganfield, in the county of Union and 5 State of Kentucky, have invented a new and useful Disk-Sharpener, of which the following is a specification.

The device forming the subject matter of this application, is a machine adapted to be 10 employed for sharpening the disks of agricultural implements.

It is the object of the present invention to provide novel means for actuating the grinding rolls, and to provide novel means 15 for adjusting the position of the disk with respect to the grinding rolls.

With the above and other objects in view which will appear as the description proceeds, the invention resides in the combination 20 and arrangement of parts and in the details of construction hereinafter described and claimed, it being understood that changes in the precise embodiment of invention herein disclosed can be made within the 25 scope of what is claimed without departing from the spirit of the invention.

In the drawings,—Figure 1 shows the invention in side elevation; Fig. 2 is an end elevation, parts being removed; Fig. 3 is a 30 horizontal section on the line A—B of Fig. 2; Fig. 4 is an end elevation, supplemental to the showing of Fig. 2; Fig. 5 is a plan of the guide plate; Fig. 6 is a side elevation of the upper grinding roll; Fig. 7 is a side elevation of the lower grinding roll; and Fig. 8 is an elevation of a modified form of 35 disk-holding means.

In carrying out the invention there is 40 provided as a primary element, a base 1, provided, if desired, along its sides, with reinforcing plates 2, and provided along its forward end with a reinforcing plate 3. Secured to the upper face of the base 1, is 45 an arched support 4, having, as seen in Fig. 3, along its inner faces, outstanding ribs 5, adapted to form slidable mountings for an upper boxing 6, and a lower boxing 7. Applied to the rear face of the support 4, is 50 a guide plate 8, seen in clearest detail in Fig. 5. The guide plate 8 is equipped with an upright slot 9, and if desired, the guide plate may likewise be supplied with outstanding ears 10, adapted to mate with similar ears

upon the base 1, securing elements being passed through the ears, to hold the guide plate 8 in place upon the rear face of the support 4. 55

Journalized for rotation in the upper boxing 6, is the upper grinding roll 11, and journalized for rotation in the lower boxing 7, is the lower grinding roll 12. The forward ends of the rolls 11 and 12 protrude beyond the forward face of the support 4, the protruding ends of the rolls 11 and 12, being tapered, as shown at 14, so as to receive 60 properly between them, the edge of the disk which is to be sharpened. As clearly appearing in Figs. 6 and 7, the grinding rolls 11 and 12 are circumferentially grooved, as 65 shown at 15, so as to engage in the slot 9 of the guide plate 8. The shaft 16 of the lower grinding roll 12 is of sufficient length to extend rearwardly, for rotation in a base-supported bearing 17. Upon the shaft 18 of the upper grinding roll 11, there is secured a pinion 19, meshing into a pinion 20, secured to the shaft 16 of the lower grinding roll 12. At this point it may be noted profitably, that the rolls 11 and 12 are not 70 parallel, the upper roll 11 being inclined 75 slightly with respect to the horizontal, so that the operative end of the said upper grinding roll 11 may engage properly with the inner, concaved face of the disk which is to be sharpened. The shaft 16 of the lower grinding roll 12 protrudes rearwardly 80 through the boxing 17. Upon the protruding end of the shaft 16, there is mounted a pinion 21, meshing into another, smaller pinion 22, secured upon the shaft 23, journalized for rotation in bearings 24, carried by 85 the base 1, to one side of the support 4. The rear end of the shaft 23 is received for rotation in a bracket 24^a, secured to the rear end face of the base 1. Upon the shaft 23, 90 between the bearings 24, there are collars 25, holding the shaft 23 against longitudinal movement. That end of the shaft 23 which protrudes beyond the bracket 24^a, may be supplied with a belt wheel 26. 95

The construction above described, presupposes that the shaft 23 is to be power-driven. Frequently, it may be desirable to operate the machine by hand, and under such circumstances, the construction may readily be 100 altered to effect this result, this alteration 105

involving merely the skill of an ordinary mechanic, and requiring no specific illustration.

In order to secure a proper coöperation between the grinding rolls 11 and 12, an adjusting means for the upper grinding roll 11 is provided, this adjusting means preferably taking the form of a screw 27, threaded into a boss 28 formed in the upper portion of the guide 4, the lower end of the screw 27 engaging with the upper boxing 26, whereby the upper grinding roll 11 is carried. For the manipulation of the screw 27, the same may be provided at its upper end with a hand wheel 29, or with any other element adapted to a like end.

Carried by the base 1, is a forwardly outstanding arm 30, preferably sustained by diverging braces 31, united at one end with the arm 30, and at their other ends, united with the base 1. Mounted for sliding movement upon the arm 30, longitudinally of the same, is a head 32, the head 32 being held in adjusted positions upon the arm 30, by means of a set screw 33 or the like, threaded into the head.

Mounted for vertical adjustment in the head 32, is an upright standard 34, to the upper end of which is pivoted, as shown at 35, a support 36, comprising spaced arms, united at their outer ends. Held for sliding movement between the arms of the support 36, is a holder 37, provided in its upper face, with an outstanding stud 38, adapted to extend through the opening in the center of the disk which is to be sharpened. This stud 38 may be of any desired construction, depending upon the nature of the disk which is to be handled in the machine.

In order to secure an adjustment of the holder 37, longitudinally of the support 36, a screw 39, provided with a suitable operating wheel 40, is threaded into the end of the support 36, and into the holder 37. An adjusting bar 41 is provided, the upper end of which is pivoted, as shown at 42, to the support 36, adjacent the free, rear end of the support. The adjusting bar 41 is supplied with a longitudinally extended slot 43, through which extends a set screw 44, or other clamping device, the set screw 44 engaging the arm 30.

In Fig. 8 of the drawings, a slight modification is shown. Referring to Fig. 8, the holder is denoted by the numeral 45, the same having an outstanding arm 46, upon which is pivoted as shown at 47, a segment 48, having an arcuate slot 49, in which is disposed a clamping element 50, adapted to enter the arm 46, to hold the segment 48 in various positions of adjustment. The segment 48 carries at its outer end, a stud 51, adapted to be engaged in the opening in the disk to be sharpened, as will be readily understood.

The operation of the device is as follows: The stud 38 is engaged in the opening of the disk which is to be sharpened, and the standard 34 is adjusted vertically, so as to position the disk for engagement between the tapered ends 14 of the grinding rolls 11 and 12. By manipulating the set screw 33, the head 32 is slid to and fro upon the arm 30, until the edge of the disk is properly positioned between the grinding rolls 11 and 12. The holder 37 may likewise be adjusted longitudinally of the support 36, by manipulating the screw 39. The proper angle with respect to the horizontal, is secured for the disk which is to be sharpened, by loosening the adjusting screw 44, and by elevating and lowering the adjusting bar 41, until the support 36 acquires the proper angle with respect to the horizontal.

From the foregoing, it will be seen that a variety of adjustments are provided, whereby the disk which is to be sharpened may be properly positioned with respect to the grinding rolls 11 and 12.

When the belt wheel 26 is rotated, rotation will be imparted to the shaft 23, the pinion 22 of which will mesh into the pinion 21, the latter pinion imparting a rotation to the lower grinding roll 12, the pinion 20 of which, meshing into the pinion 19, will impart a rotation to the upper grinding roll 11.

Referring to that form of the invention which is shown in Fig. 8, it will be seen that by loosening the clamping member 50, the segment 48 may be tilted laterally, thus permitting the disk which is carried by the stud 51 to assume different angles with respect to the grinding rolls 11 and 12, whereby the said rolls may be made to engage properly, with both the inner and outer faces of the disk which is to be sharpened.

Having thus described the invention, what is claimed is:—

1. A device of the class described comprising a supporting arm; a standard secured to the arm for adjustment both longitudinally of the arm and transversely of the arm; a support pivoted to the standard; an adjusting member pivoted to the support; means for adjustably uniting said member with the arm; a disk-holder mounted for sliding movement in the support; means for maintaining the holder in adjusted position, longitudinally of the support; and grinding mechanism disposed in operative relation with respect to the holder.

2. A device of the class described comprising a supporting arm; a head slidable longitudinally of the arm; means for securing the head in adjusted position, longitudinally of the arm; a standard adjustable in the head, transversely of the arm; a support pivoted to the standard; an adjusting member pivoted to the support and extended

across the arm; means for securing the adjusting member in different positions to the arm, to permit a raising and lowering of one end of the support; a disk-holder mounted 5 for sliding movement in the support; a screw threaded into the support and into the disk holder; and grinding mechanism disposed in operative relation to the disk-holder.

In testimony that I claim the foregoing as my own, I have hereto affixed my sig- 10 nature in the presence of two witnesses.

MORTMORE QUIRY.
